LIQUID RESERVOIR FOR STEAM IRON

Robert O. Ernest, Oak Park, Ill., assignor to Sunbeam Corporation, Chicago, Ill., a corporation of Illinois

Application May 3, 1954, Serial No. 30,296

Term of patent 14 years

(Cl. D49—6)

To all whom it may concern:

Be it known that I, Robert O. Ernest, have invented a new, original, and ornamental Design for a Liquid Reservoir for Steam Iron, of which the following is a specification, reference being had to the accompanying drawing, forming a part hereof.

Fig. 1 is an elevational view of a liquid reservoir for a steam iron embodying the new design of the present invention;

Fig. 2 is an elevational view looking at the right side of Fig. 1;

Fig. 3 is an elevational view looking at the right side of Fig. 2; and

Fig. 4 is a top plan view of Fig. 2.

I claim:

The ornamental design for a liquid reservoir for a steam iron, substantially as shown.
